(57) **CLAIM**

The ornamental design for a buggy for boxed beverages, as shown and described.

DESCRIPTION

FIG. 1 is a front perspective view of a buggy for boxed beverages showing my new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The phantom lines are not part of the claimed invention.

The broken lines in the drawings are included for the purpose of illustration and form no part of the claimed design.
